CELLOPHANE HELMET OR CAP

Lillian C. McComb, Menominee, Mich.

Application April 7, 1932, Serial No. 603,872

2 Claims. (Cl. 2—174)

This invention relates to new and useful improvements in cellophane helmets or caps and more especially to an article of this kind adapted to be worn while dressing or fitting dresses, to protect the hair, makeup and dresses.

The primary object of my invention is to provide an article of this character which is simple and economical in construction and highly efficient and durable in use.

With the foregoing and other objects in view that will appear as the nature of my invention is better understood, the same consists in the novel features of construction, combination and arrangement of parts illustrated in the accompanying drawing and more particularly pointed out in the appended claims.

In the accompanying drawing, which is for illustrative purposes only and is therefore not drawn to scale:

Figure 1 is a side elevation of a cellophane helmet or cap made in accordance with my invention.

Figure 2 is a front view.

Figure 3 is a vertical section, taken on line 3—3 of Figure 1.

Figure 4 is a similar view, taken on line 4—4 of Figure 1 and Figure 5 is a cross section, taken on line 5—5 of Figure 1.

Referring to the drawing for a more particular description of my invention and in which drawing like parts are designated by like reference characters throughout the several views, my helmet or cap, generally indicated by the reference character A, is made from cellophane, or other suitable material, and is of general hood-like form. Said helmet or cap is adapted to be worn while dressing or fitting dresses and serves to protect the hair, makeup and dresses. Specifically, the helmet or cap comprises the back 2, which fits over the back of the head and terminates approximately at the top of the neck, the corresponding side portions 3 and the front 4, which front is somewhat longer than the back 2 and extends a suitable distance below the chin.

The side portions 3 of the cap, are formed with central wedge-shaped openings 5, to provide the necessary flexibility and comfort in wearing. Said wedge-shaped openings are provided with re-inforced inturned edges 6, as shown, and strips 7 of re-inforcing tape, are applied in inverted V-shaped formation, to the outer faces of the side portions 3, at the upper ends of the aforesaid openings. Rectangular re-inforcing strips 11 are also applied to the inner faces of

the side portions 3, at the upper ends of the openings 5.

The front 4 of the cap, is provided at or near the center, with perforations 8 to facilitate breathing and the back 2 is provided with an adjustable inturned or rolled-up lower edge 9, through which the tape or cord 10 passes. Said tape or cord is adapted to be tied at the front under the chin of the wearer.

From the foregoing description, taken in connection with the drawing, it is thought that the construction, use and advantages of my invention will be readily understood without requiring a more extended explanation.

Having described my invention, what I claim as new and desire to secure by Letters Patent, is:

1. A cellophane helmet or cap adapted to be worn while dressing or fitting dresses and comprising a back portion terminating approximately at the top of the neck, a longer front portion extending below the chin and corresponding side portions with central wedge-shaped openings.

2. A cellophane helmet or cap adapted to be worn while dressing or fitting dresses as a protection for the hair, makeup and dresses and comprising a back portion terminating approximately at the top of the neck, a longer front portion extending below the chin and corresponding side portions or members with central wedge-shaped openings, inturned re-inforcing flaps at the edges of the wedge-shaped openings of the side members, an inturned or rolled up fold at the lower edge of the back portion and a tape, string or cord passing through said inturned or rolled up fold and tied at the front under the chin.

LILLIAN C. McCOMB.
